[57] CLAIM

The ornamental design for a corded, extendable stick blender, as shown and described.

DESCRIPTION

FIG. 1 is a front, left side perspective view of a corded, extendable stick blender showing my new design;

FIG. 2 is a top plan view of the corded, extendable stick blender of FIG. 1;

FIG. 3 is a front elevational view of the corded, extendable stick blender of FIG. 1;

FIG. 4 is a right side elevational view of the corded, extendable stick blender of FIG. 1;

FIG. 5 is a left side elevational view of the corded, extendable stick blender of FIG. 1;

FIG. 6 is a rear elevational view of the corded, extendable stick blender of FIG. 1;

FIG. 7 is a bottom plan view of the corded, extendable stick blender of FIG. 1; and,

FIG. 8 is a perspective view of the corded, extendable stick blender of FIG. 1, with the blender shaft in the extended position.
